DETACHABLE SUPPORT PLATFORM FOR
VEHICLE HOISTS

William A. Neilson, Northport, N. Y.

Application February 12, 1952, Serial No. 271,211

3 Claims. (Cl. 187—8.43)

1

The present invention relates to an attachment for vehicle hoists and the like and more particularly to an attachment adaptable to provide a supporting platform for a vehicle jack. Modern vehicle hoists as used in most filling stations and garages conventionally provide a controllably raisable platform or wheel support tracks on to which the vehicle is initially run, and thereafter the platform is raised to elevate the vehicle and permit work on the under parts thereof or for other reasons. In many instances when the vehicle is in a raised position on such a platform it is desirable to elevate one or more portions of the vehicle above the platform. This is most commonly done to raise one wheel of the vehicle free of the wheel support track.

It is an object of the present invention to provide a sturdy supporting platform which may be readily attached to or detached from the supporting platform of the hoist.

The ease of attachment and detachment of a structure embodying the present invention is one of its primary advantages. A detachable supporting platform embodying the present invention which is sturdy enough to support the weight of any vehicle is substantially lighter than, and much smaller than, other devices now in use for similar purposes. The ease of attachability and the light weight and small size of the structure permit speedy and convenient use of the structure. The supporting platform can be readily moved from one section of the hoist to another to permit quick successive elevation of different portions of the vehicle supported by the hoist, thus providing a great saving in labor and time.

By employing a detachable supporting platform embodying the present invention the mechanic can at all times assume a comfortable working position. The detachable supporting platform embodying the present invention may be installed or removed while the mechanic is in a standing position. Moreover the detachable supporting platform can be installed and then the hoist raised or lowered to any elevation which will provide a comfortable working position for the mechanic.

It is the further object of the present invention to provide a detachable supporting platform which will promote safety and accuracy. A mechanic can operate a jack supported by the detachable platform from a standing position and can readily observe the jack action and movement of the vehicle as it is raised. There is no necessity for the mechanic to leave the immedi-

2

ate vicinity of the hoist to operate the hoist mechanism itself, nor is there any necessity for kneeling or bending to observe the underside of the vehicle to see if the vehicle will descend and locate itself properly on the jack as the hoist is lowered. Further there is no necessity for the mechanic to speculate as to how much the vehicle has actually been raised or lowered by the jack. This is especially important and essential when attempting to line up the apertures for inserting a spring pin into the proper position.

It is also an object of the present invention to provide a device which will accomplish substantial savings in time and space. More than one man can easily and conveniently be employed at the same time, each working on separate parts of the vehicle. Moreover there is no necessity of moving the vehicle from the hoist to another location in order to raise one of the wheels into a free or non-supported position.

It is also an object of the present invention to provide a structure which eliminates the necessity of the employment of a free wheeling hoist. In other words, a hoist which raises the vehicle above the ground by supporting it through other portions than the wheels. The free wheeling hoist is undesirable in that it is difficult to work beneath the vehicle when it is supported on such a free wheeling hoist and excess time is often employed in properly locating the vehicle over the free wheeling hoist prior to its elevation. Although a device embodying the present invention does not permit the accomplishment of all the services rendered by a free wheeling hoist, it can be used to perform most of the operations accomplished while the vehicle is supported by a free wheeling hoist.

It is a further advantage of the structure embodying the present invention that it does not obstruct or reduce in any substantial way the working space in the immediate vicinity of the vehicle on the hoist. The attachable platform embodying the present invention is secured to only one side of the hoist runners and a mechanic can therefore freely move under the vehicle and can work from either side or directly in front of the detachable supporting platform without being obstructed by any other structure.

The detachable platform embodying the present invention may if desired remain secured to the vehicle hoist without interfering with or reducing the working space adjacent to the hoist or the operation of the hoist. It can thus be conveniently used for a tool or parts shelf.

It is another object of the present invention to

provide a structure that is of simple yet sturdy construction which employs a minimum of material and comprises no complex or delicate parts.

A device of the present invention may be employed whenever it is desired to support an auxiliary apparatus adjacent to a vehicle hoist. Its most common use however would be to act as a supporting platform for a lifting jack.

These and other objects and advantages of the present invention will be more readily apparent from the following description and drawing of one particular embodiment thereof. In the drawing:

Fig. 1 is an end view of the detachable supporting platform embodying the present invention mounted on the inner edge of one wheel support track of a vehicle hoist.

Fig. 2 is a vertical section through a detachable supporting platform embodying the present invention.

Fig. 3 is a view similar to Fig. 2 showing the device in the collapsed position.

Fig. 4 is a sectional view taken along line 4—4 on Fig. 2 and,

Fig. 5 is a perspective view of the device.

As can be noted in Fig. 1 the detachable supporting platform is secured through the side edge 10 of the wheel support track 11 of a conventional vehicle hoist.

In Fig. 1 a jack 12 is shown mounted on the detachable supporting platform and is in a position to engage properly the under surface of the vehicle to be elevated by the jack.

The device such as the jack 12 to be supported by the detachable platform rests on the upper surface of the base plate 13. The base plate 13 is divided into two portions by the hinge 14. The supporting platform portion 16 extends outwardly from the hinge 14 and the clamping portion 17 extends inwardly from the hinge 14.

Hingedly secured to the base plate 13 by hinge 14 is the supporting member 18. The inner holding portion 19 is shaped to the contour of the inner surface of the edge 10 of wheel support track 11, thus the inner holding portion 19 of the supporting member 18 will fit snugly against the inner surface of edge 10 of wheel support track 11.

Locking arms 21 are hingedly mounted to the supporting member 18 by hinge 22. As can be noted best from Fig. 5 the locking arms 21 extend downwardly from the hinge 22 and are connected together by cross member 23. The cross member 23 is provided with a slot 24 into which fits lug 25 which is secured to base plate 13. This lug and slot arrangement 24 and 25 helps to guide the movement of the locking arms 21 and the head 25a on lug 25 prevents separation of the base plate 13 and cross member 23.

It should be noted that the inner surface of 21 of the locking arm 21 is arcuate in shape so that it will cam securely against the outer surface of the side edge 10 of the wheel support track 11.

In order to remove the detachable supporting platform from the wheel support of the hoist the base plate 13 is pivoted about hinge 14 and moved towards the support member 18 from the position shown in Fig. 2 to the position shown in Fig. 3. This same movement causes the locking arm 21 to pivot about hinge 22 causing the cross member 23 to move outwardly relative to the plate 13, and causing the locking surface 27 to disengage from the outer surface of edge 10 of

wheel support track 11. When the device is in the collapsed position shown in Fig. 3, by lifting vertically, it can be easily moved clear of the wheel support of the hoist unit.

To secure the detachable support platform to the wheel support track 11 of the hoist unit the process is simply reversed and the inner holding portion 19 of the supporting member 18 is placed over the edge 10 of wheel support 11 while the unit is in the collapsed position and then by pivoting the plate 13 away from the supporting member 18 the unit is securely locked in position.

It should be noted that to insure that the supporting platform will be in a horizontal position the distance between the upper surface of base plate 13 and the under surface of the inner holding portion 19 of supporting member 18 should be equal to the distance between the lower surface of wheel support track 11 and the upper surface 20 of the edge 10 of wheel support track 11.

It should further be noted that for proper locking action the distance between the hinge 22 and the cam surface 27 of locking arm 21 should differ from the distance between the hinge 22 and the under surface of the inner molding portion 19 of support member 18 by substantially the thickness of the edge 10 of wheel support track 11.

It can therefore be seen that while the device is 30 sturdy and readily supports large loads, it may be easily moved from one location on the wheel support member to another location by simply pivoting into the collapsed position and then sliding it down along the wheel support track 35 11, if it is desired to keep it on the same wheel support member and on the same side. Otherwise it may simply be lifted off and placed anywhere else.

I claim:

1. A detachable supporting platform for an automobile hoist having a wheel support track with substantially vertical, upwardly extending, side edges, said detachable supporting platform comprising a base plate, an inverted U-shaped supporting member adapted to engage said side edges of the wheel support track and hingedly secured to said base plate at a point remote from either extreme edge of said base plate, said supporting member extending inwardly from its hinged connection with said base plate, said base plate having an inwardly extending portion adapted to engage the under surface of said wheel support track and an outwardly extending portion forming a platform; a locking arm hingedly secured to the outer depending arm of said U-shaped supporting member and having its inner end adapted to engage the outer surface of the side edge of the wheel support track and having the outer end thereof slidably secured to the outwardly extending portion of said base plate.

2. A detachable supporting platform for an automobile hoist having a wheel support track with substantially vertical, upwardly extending, side edges, said detachable supporting platform comprising a base plate, an inverted U-shaped supporting member adapted to engage said side edges of the wheel support track and hingedly secured to said base plate at a point remote from either extreme edge of said base plate, said supporting member extending inwardly from its hinged connection with said base plate, said base plate having an inwardly extending portion adapted to engage the under surface of said wheel support track and an outwardly extending

portion forming a platform; two locking arms each hingedly mounted at a point remote from their extreme edges to the outer depending arm of said supporting member, said locking arms being connected by a cross member and said cross member being slidably secured to the outwardly extending portion of said base plate.

3. A detachable supporting platform as claimed in claim 2 wherein said cross member has a slot

therein and including a lug secured to said base plate and adapted to engage in said slot.
